SLUG CASTING MACHINE

Harold A. Burt, St. Albans, N. Y., assignor to
Mergenthaler Linotype Company, a corpora-
tion of New York

Application March 2, 1939, Serial No. 259,379

20 Claims. (Cl. 199—60)

This invention relates to slug casting machines of the general organization represented in U. S. Letters Patent No. 436,532 to O. Mergenthaler, wherein circulating matrices are released from a magazine in the order in which their characters are to appear in print, and then assembled in line, the composed line presented against the face of a slotted mold, the mold filled with molten metal to form a type bar or slug against the matrices which produce the type characters thereon, the matrices returned through distributing mechanism to the magazine from which they started, and the type bar or slug ejected from the mold by a blade which advances against the rear edge thereof.

To enable slugs of different measures to be cast, such machines are provided with a plurality of molds (usually four in number) mounted on a disc which is rotated by a power driven pinion. In the casting cycle, the disc is first given a quarter rotation to bring the mold in use into slug casting position, and, then after the slug has been cast, a three-quarter rotation to bring the mold back to its original or slug ejecting position. In selecting a mold for use when the machine is at rest, the mold disc turning pinion is pulled forward to uncouple it from its driving mechanism, then rotated manually to bring the desired mold on the disc into operative position, and then pushed rearwardly to recouple it to its driving mechanism.

The ejector blade employed in such machines ordinarily comprises a series of sections arranged edge to edge in contacting relation, and suitable devices are employed whereby any desired number of sections can be connected to the ejector slide while the others remain at rest. In consequence, every time a different mold is selected for use, an adjustment must be made in the number of effective blade sections so that their combined width will accord with the length of the slot in the mold selected.

According to the present invention, the required adjustment in the width of the ejector blade is effected during the mold changing operation. To this end, the machine is equipped with suitable mechanism which acts to restore the ejector blade to a minimum width each time the mold disc turning pinion is pulled forward to uncouple it from its driving connection preparatory to the rotation of the disc in selecting a new mold, and which thereafter acts under the control of the newly selected mold to adjust the width of the ejector blade in accordance with the length of the mold slot as the pinion is pushed rearwardly to recouple it to its driving mechanism.

For a detailed description of the invention, reference will be made to the accompanying drawings wherein the invention has been shown in preferred form, although obviously many variations and modifications may be made therein which will still be comprised within its spirit. It is to be understood, therefore, that the invention is not limited to any specific form or embodiment except insofar as such limitations are specified in the appended claims.

Referring to the drawings:

Fig. 1 is a front elevation of a portion of a slug casting machine embodying the present invention;

Fig. 2 is a side elevation, partly in section, showing the train of connections between the mold disc turning pinion and the ejector adjusting devices;

Fig. 3 is a side elevation, partly in section, showing the mold disc turning pinion uncoupled from its driving mechanism;

Fig. 4 is a front view showing in detail the adjustable stop plate and its actuating mechanism;

Fig. 5 is a side elevation (similar to Fig. 3) showing the mold disc turning pinion coupled to its driving mechanism;

Fig. 6 is a plan view, partly in section, showing the relative position of the stop plate, its actuating arm, and the arresting screw against which the stop plate banks when in normal position;

Fig. 7 is a similar view showing the stop plate in a different set position; and

Fig. 8 is a perspective view of a detail.

In Fig. 1, the machine is shown with a mold disc 10 equipped with four molds designated 12 em, 15 em, 24 em and 30 em, respectively, the last mentioned mold being the one in operative position. During a machine cycle of operation, the mold disc 10 is rotated by a power driven pinion 11, first, through ninety degrees in a counter-clockwise direction to carry the mold then in use from its vertical ejecting position to a horizontal casting position, and thereafter through two hundred seventy degrees in the same direction to carry the mold back to its vertical ejecting position.

As usual, the mold disc turning pinion 11 is provided with a forwardly projecting hub portion 12 rotatably mounted on a sleeve 13 pinned to the front end of a fore-and-aft power driven shaft 14. At its rear end, the sleeve 13 is provided with a collar 15 having a radial arm 16 from which a coupling pin 17 projects forwardly into a hole or recess 18 formed in the rear face of the pinion 11. The hub portion 12, at its forward end, terminates in a conical face 19 which joins it with a reduced sleeve 20 positioned about a stud 21 threaded into

the forward end of the shaft 14 and forming a housing for a compression spring 22, one end of which bears against the head of the stud 21 and the other end of which bears against a bearing collar 23. When it is desired to change the mold in use, the pinion 11 is pulled forward by means of a hand wheel 24, carried by the outer end of the reduced sleeve 20, until the coupling pin 17 is disengaged from the recess 18, and the pinion 10 is then rotated manually to turn the mold disc 10 until the selected mold is brought into operative position, by which rotation the recess 18 in the pinion 11 is brought in alignment with the pin 17, whereupon the pinion 11 is released and forced rearwardly by the spring 22 to engage the pin 17 in the recess 18 and so recouple the pinion 11 to the drive shaft 14.

The slug ejecting mechanism herein employed is of the sort shown and described in U. S. Letters 20 Patent No. 967,976 granted to J. R. Rogers on August 23, 1910. In general, it comprises a series of blade sections 30 arranged edge to edge and guided between a side plate 31 and the mold slide 32 (Fig. 2). The sections 30 are actuated by individual horizontal slides 33 mounted in grooves formed in the mold slide 32. A vertical bar 34, slidably mounted in a groove cut in the face of an ejector slide 35 behind the rear ends of the horizontal slides 33, serves to connect the slide 35 to any selected number of blade sections 30. The lower end of the vertical bar 34 is provided with an offset portion 36 slidably mounted on a fore-and-aft rod 37 carried by a plate 38 which, in turn, is slidably mounted in a bracket 39 secured 35 to the main frame of the machine.

Coming now to the present invention, automatic means are provided for so positioning the vertical slide bar 34 during the mold changing operation that the combined width of the blade sections 30 actuated thereby as the ejector slide 35 moves forward corresponds to the length of the slot in the mold selected. To this end, there is provided between the mold turning pinion 11 and the bar actuating plate 38 a system of levers 40 whereby the uncoupling movement of the pinion 11 will shift the bar 34 to its lowermost or starting position and whereby the recoupling movement of the pinion 11 will shift the bar 34 to its required final position as determined by the slot length of the new mold brought into operative position by the rotary adjustment of the mold disc 10, the latter being provided with variant devices, one for each mold, which cooperate during the rotary adjustment of the mold disc 10 with an adjustable stop plate carried by one lever of the system and which set it in whatever position is necessary to arrest the upward movement of the bar 34 in selecting the required number of blade sections 30 for the newly selected mold.

The system of levers between the mold turning pinion 11 and the bar actuating plate 38 includes a vertical rocker arm 40 mounted beneath the pinion 11 on a shaft 41 journaled in bearings 42 of a bracket 43 secured to the main frame of the machine. The bifurcated upper end of the rocker arm 40 is provided with an anti-friction roller 44 positioned in the path traveled by the conical face 19 of the pinion 11 as the latter is pulled forward to uncouple it from the shaft 14. Pivottally connected to the lower end of the rocker arm 40 is a fore-and-aft link 45 whose rear end is provided with a pin 46 positioned in an open-ended slot 47 formed in the upper end of the vertical arm of a bell-crank lever 48 mounted on a shaft 75 49 journaled in bearings 50 of a bracket 51 se-

cured to the main frame of the machine. A vertical link 52, at its upper end, is pivotally connected to the bell-crank lever 48 at the outer end of the horizontal arm thereof, and at its lower end, the vertical link 52 is connected to a laterally disposed or cross arm 53 at the left end thereof through the medium of a stud 54. The cross arm 53 is pivotally mounted between its ends on a stud 55 carried by an extension of the bracket 51. At its right end, the cross arm 53 is pivotally connected to the lower end of an adjustable link 57, whose upper end is pivotally connected to the forward end of an off-set fore-and-aft rocker arm 58. The rocker arm 58 is pivotally mounted between its ends on a stud 59 carried by a bracket 60 secured to the main frame of the machine, and at its rear end it is provided with an open-ended slot 61 through which extends a pin 62 carried by the bar actuating plate 38.

Between its pivotal axis and the lower end 20 thereof, the rocker arm 40 is provided with a horizontal groove in which a stop plate 65 is slidably mounted. Normally, the plate 65 banks against a screw 66, carried by a depending arm 67 which forms a part of the bracket 43, and is 25 locked in set position by means of a pivoted latch 68 which engages ratchet teeth 69 formed on the upper edge thereof (see Figs. 2 and 4).

When the pinion 11 is pulled forward to uncouple it from shaft 14 during a mold changing 30 operation, the anti-friction roller 44 is engaged by the conical face 19 and the lower end of the rocker arm 40 (see Fig. 3) is moved to its rearmost position against the action of a pull spring 40^a to position the stop plate 65 opposite an adjusting screw 72 carried by the lower end of an actuating arm 73 (see Fig. 4), which latter is pivotally mounted at its upper end on a stud 74 carried by a bracket 75 forming a part of the usual lateral arm or extension 76 of the mold slide. As 40 the lower end of the rocker arm 40 moves to its rearmost position, the rear end of the latch 68 is depressed by its engagement against a trackway 78 formed on the bracket 54, and the front end thereof is freed from engagement with the ratchet 45 teeth 69. A pull spring 71 then acts to shift the stop plate 65 to the right to carry the right end thereof against the adjusting screw 72. To limit its movement to the right under the influence of the pull spring 71, the plate 65 is provided with 50 an arresting block 77 which banks against a shoulder 78 on the rocker arm 40 when the plate 65 is in its rightmost position (see Fig. 4).

Also when the lower end of the rocker arm 40 is moved rearwardly against the action of the pull spring 40^a, the bell-crank lever 48 is rotated counter-clockwise about its pivotal axis through the medium of the fore-and-aft link 45. Such counter-clockwise rotation of the bell-crank lever 48 forces the vertical link 52 downwardly and so rocks the cross arm 53 counter-clockwise about the stud 55. As the cross arm 53 thus rotates counter-clockwise, the front end of the fore-and-aft rocker arm 58 is forced upwardly and the rear end thereof is forced downwardly through 65 the medium of the connecting link 57. As the rear end of the fore-and-aft rocker arm 48 is forced downwardly, the bar actuating plate 38 carrying the fore-and-aft rod 37 is pulled downwardly to its lowermost position, carrying with it 70 the bar 34 to restore the effective width of the ejector to a single 4 em section attached to the lowermost slide 33, as shown by the dotted lines in Fig. 2.

It is to be noted that during the later part of 75

the rearward movement of the lower end of the rocker arm 40, that is to say, after the effective width of the ejector has been restored to 4 ems, the pin 46 on the rear end of the link 45 moves outwardly for a limited distance along the open-ended slot 47 in the upper end of the bell-crank lever 48 (see Fig. 3), this lost motion in the system of levers during the uncoupling movement of the driving pinion 11 being provided for reasons subsequently to appear.

After the stop plate 65 has been brought against the banking screw 72 in response to the uncoupling movement of the pinion 11, it is reset during the rotary manual adjustment of the mold disc 10 in whatever position is necessary to arrest the upward movement of the bar 34 in selecting the required number of blade sections 33 for the newly selected mold. As stated heretofore, the resetting of the stop plate 65 is effected through the medium of variant devices mounted on the mold disc, and which, in the present embodiment of the invention, comprise four selector blocks 80 of different sizes, one being positioned at the leading or foremost end of each of the four molds on the disc 10, as determined by the usual counter-clockwise rotation of the disc. When the mold disc 10 is rotated counter-clockwise to bring a selected mold into operative position, the selector block 80 at the leading or foremost end of the mold positioned opposite the selected mold engages and depresses a horizontal arm 81 which cooperates with the aforementioned actuating arm 73, moving the stop plate 65 to the left a distance dependent on the size of the particular block in action.

When the pinion 11 is recoupled to the shaft 14 after the rotary adjustment of the mold disc, the pull spring 40^a acts to rock the arm 40 about its pivotal axis and so force the lower end thereof forwardly until further movement thereof is prevented by the engagement of the stop plate 65 against the banking screw 66 (see Fig. 1). During the initial forward movement of the lower end of the rocker arm 40, that is to say, while the lost motion in the system of levers is being absorbed, the rear end of the latch 68 is carried out of engagement with the trackway 70 and the forward end thereof is carried into engagement with the ratchet teeth 69 by means of a spring 82 to lock the stop plate in the position to which it was set during the rotary adjustment of the mold disc (see Fig. 5). Also during the initial forward movement of the lower end of the rocker arm 40, the stop plate 65 is carried away from the adjusting screw 72 and so remains undisturbed during the normal operation of the machine (see Fig. 6). During the latter part of the forward movement of the rocker arm 40, that is to say, after the lost motion in the system of levers has been absorbed, the cross arm 53 is rotated clockwise through the medium of the fore-and-aft link 45, the bell-crank lever 48 and the vertically disposed link 52 (see Figs. 1 and 2). As the cross arm 53 rotates clockwise, the forward end of the fore-and-aft rocker arm 58 is pulled downwardly through the medium of the connecting adjustable link 57 and the rear end thereof is forced upwardly; and as the rear end of the rocker arm 58 is forced upwardly, the slide plate 38 carrying the fore-and-aft rod 37 is likewise forced upwardly, carrying with it the bar 34 until further clockwise rotation of the cross arm 53 is arrested by the engagement of the stop plate 65 against the banking screw 66.

Adjacent the left end thereof, the stop plate 65 is provided with a projecting flat face 83 and with

an inclined face 84 which leads from the front face of the stop plate 65 to the left end of the flat face 83 (see Figs. 4, 6 and 7). The stop plate 65 is so positioned in the lower end of the rocker arm 40 that when the front face thereof engages the banking screw 66, the clockwise rotation of the cross arm 53 is arrested after the bar 34 has been forced upwardly behind all the slides 33 for a total effective ejector width of 30 ems. The distance that the flat face 83 projects outwardly beyond the front face of the stop plate 65 is such that, immediately after the lost motion in the system of levers is absorbed, it engages the banking screw 66 to prevent the clockwise rotation of the cross arm 53 before the rod 34 is carried upwardly beyond the lowermost slide 33, thus keeping the effective width of the ejector at 4 ems. The pitch of the sloping face 84 is such that when it, at any given point along its length, engages the banking screw 66 the clockwise rotation of the cross arm 53 is arrested after the bar 34 is elevated behind a corresponding number of slides 33. In consequence, by employing selector blocks 80 which move the stop plate 65 to the left during the rotary adjustment of the mold disc 10 until the front face of the plate (Fig. 2) or the projecting flat face 83 (Fig. 5) or the tapered face 84 (Fig. 7) is behind the banking screw 66, it is thus possible to obtain automatically a setting of the ejector which will accord respectively with a 30 em mold, or a 4 em mold, or a mold between these two extremes as, for example, one or another of the 12 em, 15 em and 24 em molds shown in Fig. 1.

The stop plate actuating arm 81, in projecting into the path traveled by the selector blocks 80 during the rotation of the mold disc 10, will be actuated thereby regardless of the direction in which the mold disc is rotated. However, if the engagement of the horizontal arm 81 by the blocks 80 during the clockwise rotation of the disc affected the set screw arm 73, it is quite possible that the lower end thereof would be swung into the path of the molds and cause considerable damage. To prevent such an occurrence, the lower end of the arm 73 banks against a stop pin 85 and the upper end thereof is provided with an offset shoulder 86 (see Fig. 8). The left end of the horizontal arm 81 is pivotally mounted on the same stud 74 upon which the upper end of the actuating arm 73 is mounted, and it is provided with a vertical end face 87, with a bottom flat face 88 which rests on the offset shoulder 86 and which projects to the right from a vertical line through the center of the stud 74, and with a rounded corner 89 which joins the vertical end face 87 and the bottom flat face 88. In consequence, when the horizontal arm 81 is actuated during the counter-clockwise rotation of the mold disc 10, the engagement between the bottom flat face 88 of the horizontal arm 81 and the offset shoulder 86 of the arm 73 causes the lower end of the arm 73 to swing to the left, but when the horizontal arm 81 is actuated during the clockwise rotation of the mold disc 10, the rounded corner 89 rolls on the offset shoulder 86 against the action of an offset leaf spring 90 and so leaves the arm 73 undisturbed.

At certain times, the right hand end of the stop plate 65 will extend beyond the end of the adjusting screw 72 on the actuating arm 73 when the pinion 11 is pulled forward to uncouple it from shaft 14. To prevent damage when this condition exists, the actuating arm 73 is made up of two sections 91 and 92 respectively. The lower end of the upper section 91 terminates in a sleeve

93 in which the upper end of the lower section 92 is rotatably mounted. The sleeve 93 is provided with a short circumferential slot 94 through which extends a pin 95 carried by the journaled upper 5 end of the lower section 92. A spring 96, positioned about the lower section 92 with one of its ends secured thereto and its other end secured to the sleeve 93, maintains the pin 95 against the front end of the slot 94. In consequence, in the 10 event the right hand end of the stop plate 65 engages the adjusting screw 72 when the pinion 11 is uncoupled from the shaft 14, the lower end section 92 simply rotates rearwardly against the action of the spring 96.

15 Having thus described my invention, what I claim is:

1. In a slug casting machine equipped with a plurality of slotted molds mounted on a rotatable disc which is adjustable by its driving pinion to bring any selected mold into use, said pinion being movable to uncouple it from and recouple it with the driving mechanism before and after such rotary adjustment of the mold disc, respectively, an ejector mechanism adjustable as to 20 blade width to correspond with the slot length of the selected mold, and a shiftable element to effect such adjustment of the ejector mechanism, the combination of means actuated by the uncoupling and recoupling movements of the driving pinion for shifting the ejector device first to a given starting position and then to the required 25 final position respectively, and means actuated by the mold disc during the rotary adjustment thereof for determining said final position of the 30 ejector adjusting element.

2. A combination as specified in claim 1, wherein the means for determining the final position of the ejector adjusting element include an adjustable stop device which is set in one position or another according to the slot length in the 40 newly selected mold.

3. A combination as specified in claim 1, wherein the means for determining the final position of the ejector adjusting element include an adjustable stop device cooperative with variant devices carried by the rotary mold disc.

4. In a slug casting machine equipped with a plurality of slotted molds mounted on a rotatable disc which is adjustable by its driving pinion to bring any selected mold into use, said pinion being movable to uncouple it from and recouple it with the driving mechanism before and after such rotary adjustment of the mold disc, respectively, an ejector mechanism adjustable as to 50 blade width to correspond with the slot length of the selected mold, and a shiftable element to effect such adjustment of the ejector mechanism, the combination of a system of levers between the driving pinion and the ejector adjusting element operative by the uncoupling movement of the pinion to shift said adjusting element to a given starting position and operative by the recoupling movement of the pinion to shift said element to the required final position, and an adjustable stop device carried by one lever of the system to determine such final position of the 55 ejector adjusting element, variant devices carried by the rotary adjustment thereof to set the stop device in one position or another according to the slot length of the newly selected mold, and automatic means for locking the stop device in its set position.

5. In a slug casting machine equipped with a plurality of slotted molds mounted on a rotatable disc which is adjustable by its driving pinion to bring any selected mold into use, said pinion being movable to uncouple it from and recouple it with the driving mechanism before and after such rotary adjustment of the mold disc, respec-

tively, an ejector mechanism adjustable as to blade width to correspond with the slot length of the selected mold, and a shiftable element to effect such adjustment of the ejector mechanism, the combination of a system of levers between the driving pinion and the ejector adjusting element operative by the uncoupling movement of the pinion to shift said adjusting element to a given starting position and operative by the recoupling movement of the pinion to shift said element to the required final position, and an adjustable stop device carried by one lever of the system to determine such final position of the ejector adjusting element, said stop device being actuated to its set position by the mold disc during the rotary adjustment thereof.

6. In a slug casting machine equipped with a plurality of slotted molds mounted on a rotatable disc which is adjustable by its driving pinion to bring any selected mold into use, said pinion being movable to uncouple it from and recouple it with the driving mechanism before and after such rotary adjustment of the mold disc, respectively, an ejector mechanism adjustable as to blade width to correspond with the slot length of the selected mold, and a shiftable element to effect such adjustment of the ejector mechanism, the combination of a system of levers between the driving pinion and the ejector adjusting element operative by the uncoupling movement of the pinion to shift said adjusting element to a given starting position and operative by the recoupling movement of the pinion to shift said element to the required final position, and an adjustable stop device carried by one lever of the system to determine such final position of the ejector adjusting element, said stop device being actuated to its set position during the rotation of the mold disc by variant devices carried by said disc.

7. In a slug casting machine equipped with a plurality of slotted molds mounted on a rotatable disc which is adjustable by its driving pinion to bring any selected mold into use, said pinion being movable to uncouple it from and recouple it with the driving mechanism before and after such rotary adjustment of the mold disc, respectively, an ejector mechanism adjustable as to blade width to correspond with the slot length of the selected mold, and a shiftable element to effect such adjustment of the ejector mechanism, the combination of a system of levers between the driving pinion and the ejector adjusting element operative by the uncoupling movement of the pinion to shift said adjusting element to a given starting position and operative by the recoupling movement of the pinion to shift said element to the required final position, an adjustable stop device carried by one lever of the system to determine such final position of the ejector adjusting element, variant devices mounted on the mold disc and acting selectively by the rotary adjustment thereof to set the stop device in one position or another according to the slot length of the newly selected mold, and automatic means for locking the stop device in its set position.

8. In a slug casting machine equipped with a plurality of slotted molds mounted on a rotatable disc which is adjustable by its driving pinion to bring any selected mold into use, said pinion being movable to uncouple it from and recouple it with the driving mechanism before and after such rotary adjustment of the mold disc, respectively, an ejector mechanism adjustable as to

blade width to correspond with the slot length of the selected mold, and a shiftable element to effect such adjustment of the ejector mechanism, the combination of a system of levers between 5 the driving pinion and the ejector adjusting element operative by the uncoupling movement of the pinion to shift said adjusting element to a given starting position and operative by the recoupling movement of the pinion to shift said element to the 10 required final position, an adjustable stop device carried by one lever of the system to determine such final position of the ejector adjusting element, variant devices mounted on the mold disc and acting selectively by the rotary adjustment thereof to 15 set the stop device in one position or another according to the slot length of the newly selected mold, and automatic means for locking the stop device in its set position, said locking means being actuated by the uncoupling movement of 20 the driving pinion to release the stop device and permit it to assume a starting position preparatory to the rotary adjustment of the mold disc, and said locking means being actuated by a slight lost motion in the recoupling movement of the 25 driving pinion to hold the stop device in its set position as determined by the rotary adjustment of the mold disc.

9. In a slug casting machine equipped with a plurality of slotted molds mounted on a rotatable 30 disc which is adjustable by its driving pinion to bring any selected mold into use, said pinion being movable to uncouple it from and recouple it with the driving mechanism before and after such rotary adjustment of the mold disc, respectively, an ejector mechanism adjustable as to 35 blade width to correspond with the slot length of the selected mold, and a shiftable element to effect such adjustment of the ejector mechanism, the combination of a system of levers, including 40 a rocker arm, between the driving pinion and the ejector adjusting element operative by the uncoupling movement of the pinion to shift said adjusting element to a given starting position and operative by the recoupling movement of 45 the pinion to shift said element to the required final position, and an adjustable stop plate carried by said rocker arm to determine such final position of the ejector adjusting element.

10. In a slug casting machine equipped with a plurality of slotted molds mounted on a rotatable 50 disc which is adjustable by its driving pinion to bring any selected mold into use, said pinion being movable to uncouple it from and recouple it with the driving mechanism before and after such rotary adjustment of the mold disc, respectively, an ejector mechanism adjustable as to 55 blade width to correspond with the slot length of the selected mold, and a shiftable element to effect such adjustment of the ejector mechanism, the combination of a system of levers, including 60 a rocker arm carrying an adjustable stop plate, between the driving pinion and the ejector adjusting element operative by the uncoupling movement of the pinion to shift said adjusting element to the required final position as determined by the location of 65 said plate, and means responsive to the rotary adjustment of the mold disc for locating said plate in one position or another according to the slot length of the newly 70 selected mold.

11. In a slug casting machine equipped with a plurality of slotted molds mounted on a rotatable 75 disc which is adjustable by its driving pinion to bring any selected mold into use, said pinion being movable to uncouple it from and recouple

it with the driving mechanism before and after such rotary adjustment of the mold disc, respectively, an ejector mechanism adjustable as to 5 blade width to correspond with the slot length of the selected mold, and a shiftable element to effect such adjustment of the ejector mechanism, the combination of a system of levers, including 10 a rocker arm carrying an adjustable stop plate, between the driving pinion and the ejector adjusting element operative by the uncoupling movement of the pinion to shift said adjusting element to a given starting position and operative by the recoupling movement of the pinion to shift said element to the required final position as determined by the location of said plate, and 15 variant devices mounted on the mold disc and adapted during the rotary adjustment thereof to locate said plate in one position or another according to the slot length of the newly selected 20 mold.

12. In a slug casting machine equipped with a plurality of slotted molds mounted on a rotatable disc which is adjustable by its driving pinion to bring any selected mold into use, said pinion being movable to uncouple it from and recouple 25 it with the driving mechanism before and after such rotary adjustment of the mold disc, respectively, an ejector mechanism adjustable as to 30 blade width to correspond with the slot length of the selected mold, and a shiftable element to 35 effect such adjustment of the ejector mechanism, the combination of a system of levers, including a rocker arm carrying an adjustable stop plate, between the driving pinion and the ejector adjusting element operative by the uncoupling 40 movement of the pinion to shift said adjusting element to a given starting position and operative by the recoupling movement of the pinion to shift said element to the required final position as determined by the location of said plate, 45 means responsive to the rotary adjustment of the mold disc for locating said plate in one position or another according to the slot length of the newly selected mold, and means for locking said plate in the position to which it is set during 50 the rotary adjustment of the mold disc.

13. In a slug casting machine equipped with a plurality of slotted molds mounted on a rotatable disc which is adjustable by its driving pinion to bring any selected mold into use, said pinion being movable to uncouple it from and recouple 55 it with the driving mechanism before and after such rotary adjustment of the mold disc, respectively, an ejector mechanism adjustable as to blade width to correspond with the slot length 60 of the selected mold, and a shiftable element to effect such adjustment of the ejector mechanism, the combination of a system of levers, including a rocker arm carrying an adjustable stop plate, between the driving pinion and the ejector 65 adjusting element operative by the uncoupling movement of the pinion to shift said adjusting element to a given starting position and operative by the recoupling movement of the pinion to shift said element to the required final position as determined by the location of said plate, 70 means responsive to the rotary adjustment of the mold disc for locating said plate in one position or another according to the slot length of the newly selected mold, and means for locking said plate in the position to which it is set during 75 the rotary adjustment of the mold disc, said locking means being actuated by the uncoupling movement of the driving pinion to release the

stop plate and permit it to assume a starting position preparatory to the rotary adjustment of the mold disc, and said locking means being actuated by a slight lost motion in the recoupling 5 movement of the driving pinion to hold the stop plate in its set position as determined by the rotary adjustment of the mold disc.

14. In a slug casting machine equipped with a mold disc having a plurality of slotted molds 10 interchangeable in operative position with each other, an ejector mechanism adjustable as to blade width to correspond with the slot length of the mold in operative position, said mechanism comprising a main actuating slide and a 15 series of blade sections arranged in superposed edge to edge relation, and a shiftable element to connect any selected number of blade sections to the main actuating slide, the combination of means actuated during the interchange of molds 20 for first shifting the ejector connecting element to a given starting position and then to its required final position, and means controlled by the newly selected mold for determining such final position of the ejector connecting element.

15. In a slug casting machine equipped with a mold disc having a plurality of slotted molds 25 interchangeable in operative position with each other, an ejector mechanism adjustable as to blade width to correspond with the slot length of the mold in operative position, said mechanism comprising a main actuating slide and a series of blade sections arranged in superposed edge to edge relation, and a shiftable element to connect any selected number of blade sections to the main actuating slide, the combination of a system of levers actuated during the interchange 30 of molds for first shifting the ejector connecting element to a given starting position and then to its required final position, and means controlled by the newly selected mold for determining such final position of the ejector connecting element.

16. In a slug casting machine equipped with a mold disc having a plurality of slotted molds 45 interchangeable in operative position with each other, an ejector mechanism adjustable as to blade width to correspond with the slot length of the mold in operative position, said mechanism comprising a main actuating slide and a 50 series of blade sections arranged in superposed edge to edge relation, and a shiftable element to connect any selected number of blade sections to the main actuating slide, the combination of a system of levers actuated during the interchange 55 of molds for first shifting the ejector connecting element to a given starting position and then to its required final position, and a stop device controlled by the newly selected mold for determining such final position of the ejector connecting element.

17. In a slug casting machine equipped with a mold disc having a plurality of slotted molds 60 interchangeable in operative position with each other, an ejector mechanism adjustable as to blade width to correspond with the slot length of the mold in operative position, said mechanism comprising a main actuating slide and a 65 series of blade sections arranged in superposed edge to edge relation, and a shiftable element to connect any selected number of blade sections to the main actuating slide, the combination of a system of levers actuated during the inter-

change of molds for first shifting the ejector connecting element to a given starting position and then to its required final position, a stop device for arresting the movement of said levers, and means actuated during the interchange of 5 molds for so positioning said stop device that the movement of the levers is arrested thereby when the ejector connecting element is shifted to its required final position.

18. In a slug casting machine equipped with 10 a mold disc having a plurality of slotted molds interchangeable in operative position with each other, an ejector mechanism adjustable as to blade width to correspond with the slot length of the mold in operative position, said mechanism comprising a main actuating slide and a 15 series of blade sections arranged in superposed edge to edge relation, and a shiftable element to connect any selected number of blade sections to the main actuating slide, the combination of 20 a system of levers actuated during the interchange of molds for first shifting the ejector connecting element to a given starting position and then to its required final position, a stop device for arresting the movement of said levers, and 25 a selector block on said mold disc adapted to so position said stop device during the interchange of molds that the movement of the levers is arrested thereby when the ejector connecting element is shifted to its required final position. 30

19. In a slug casting machine equipped with a mold disc having a plurality of slotted molds 35 interchangeable in operative position with each other, an ejector mechanism adjustable as to blade width to correspond with the slot length of the mold in operative position, said mechanism comprising a main actuating slide and a series of blade sections arranged in superposed edge to edge relation, and a shiftable element to connect any selected number of blade sections 40 to the main actuating slide, the combination of a system of levers actuated during the interchange of molds for first shifting the ejector connecting element to a given starting position and then to its required final position, a stop 45 device for arresting the movement of said levers, and a selector block on said disc adapted to so position said device as a newly selected mold is brought into operative position that the movement of the levers is arrested thereby when the 50 ejector connecting element is shifted to its required final position.

20. In a slug casting machine, the combination of a disc carrying a plurality of slotted molds, a pinion movable to uncouple it from and 55 recouple it with the driving mechanism and operable in its uncoupled position to rotate the disc to bring any selected mold into use, an ejector mechanism adjustable as to blade width to correspond with the slot length of the selected 60 mold, said mechanism comprising a main actuating slide and a series of blade sections arranged in superposed edge to edge relation, a shiftable element to connect any selected number of blade sections to the main actuating slide, and means 65 actuated by the uncoupling and recoupling movements of the pinion for shifting the ejector connecting element first to a given starting position and then to the required final position, respectively, under the control of a newly selected mold. 70
